UNITED STATES PATENT OFFICE.

HARRY J. NICHOLS, OF WASHINGTON, DISTRICT OF COLUMBIA.

TACTUAL INDICATOR.

Application filed April 17, 1924. Serial No. 707,053

This invention relates to tactful indicating means and more particularly to indicating means whereby one of a plurality of similar small portable articles such as keys may be readily distinguished from the others by tactful observation in the dark, for example, as well as visually when the light will permit.

In order that a clearer perception of the present invention may be readily had, one embodiment or application of the invention will be hereinafter described with relation to keys although it is, of course, to be understood that the invention is not to be limited to the specific articles to which it is applied or to the exact manner shown for indicating these articles.

As is well-known to all users of keys, the majority of keys now in use are of a flat type generally known as tumbler or Yale lock or Corbin lock keys. These keys have a plurality of tumbler engaging projections along one edge and one or more grooves along one side surface. While twenty may be carried on a key ring or holder only three or four are used daily or frequently. In using any one of these keys, it is first necessary to determine which of the various keys on the ring is desired by observation and, second, to insure that the key is placed right-side up in the lock. At times this is exceedingly difficult owing to darkness or a failure in memory to properly remember the configuration of the key tumblers applicable to a particular lock, for some keys differ from others only by very slight details.

The present invention is, therefore, designed to remedy this situation by marking the keys in such a manner that the desired key may readily be selected in the dark and inserted in the correct position in the lock to which the specific key is applicable.

A further object is to provide a tactful indicator for keys which may be inexpensively manufactured and readily applied.

A further object is to provide an indicator of the above type which will be durable and substantial in construction, not likely to wear out or off with age or continued use as with luminous paint.

A further object is to provide an indicator of the above character always ready for immediate use, which will not be bulky in size or have projections of such character as will injure the pocket, for example.

Other objects will be in part obvious and

in part hereinafter pointed out in connection with the following analysis of this invention and in connection with the accompanying sheet of drawings illustrating two of various possible embodiments.

Figures 1 to 4 of this drawing show, for example, in elevation four keys, each of which is provided with different tactful indicating marks adjacent the grip or that part of the key which is grasped when in operation.

Figure 5 is a sectional view of Figure 1.

Figure 6 shows a modification, and,

Figure 7 shows one of the indicating devices as manufactured, according to Fig. 6 and slightly enlarged.

Referring to Figs. 1 to 5, there is shown a number of keys 5 having head or shank portions 6 with holes 7 therein for attachment to a key-ring or the like. Indicators in the form of rivets 10 are inserted in holes 8 drilled in the head or shank portions, and are smoothed down at their ends, leaving the slightly raised rivet head projecting over one face of the head or shank portion 6, as shown in Fig. 5. The holes themselves could be used indicating the key desired, but these are more confusing and not as easily discernible to the average person by a sense of touch. The indicators may also be embossed on the keys or other articles when produced by a stamping or punching process.

The shape or configuration of the rivet head acting as the indicator is conventionally represented as circular in Figures 1 to 5. It is to be understood, however, that this shape of the rivet head is arbitrary, and may embody any design or configuration to provide the maximum of tactful indication. Indicators or projections 10 are preferably arranged on that face of the head or shank portion 6 with which the thumb contacts when the key is in its proper position for insertion in the lock.

The holes 8 may be placed at any desired point on the body, or the projections could be placed upon the peripheral edge if so desired. Instead of using projections, notches could be cut in the edge although this form is not as desirable owing to the fact that an increase in the rough edges is harder on the wear and tear of the pocket in which the keys are carried.

The present invention also has an added feature, namely, that the keys can be marked in an identifying manner in the order in which they are usually used during the day.

For example, it may be stated that the average business man uses every day only three or four keys such as his house, his garage, his office and his desk.

5 It would, therefore, be perhaps desirable to mark the keys in this order, that is, he leaves his house in the morning, which house key would have one indicator; second, goes into his garage, which key would have two 10 indications; third, goes to his office which key has three indications and, fourth, opens his desk, which would have four indications. Placing this order of events in his mind it is a very simple matter for him to select 15 the desired key without so much as a glance and know purely by a sense of touch that he not only has the right key for the desired lock but also, by reason of the indicating means projecting laterally in a predetermined 20 relation from the flat face of the grip portion or head, that he is inserting the key in its right position in said lock.

In Figures 6 and 7 is shown a modification. Here the key is provided with four 25 small holes 11 arranged in the form of a square. Into these holes are inserted one or more of the indicators 12 shown in Figure 7 and lightly tapped with a hammer which rivets over the inserted end and holds the 30 indicator in the desired position. Thus an almost unlimited number of combinations may be provided for, according to the number of indicators used and their relative position on the key body.

35 The indicator while largely tactful also permits of ready observation enabling one to more quickly select the desired article rather than to compare the number of notches on the key edge.

40 It is thus seen that the present invention provides a simple and practical mechanism or means for indicating at any time which

one of a plurality of self-contained similar portable devices is adapted to be used as well as the assurance that such article is 45 used in the proper manner with relation to its cooperating part. While I have described the invention with relation to its application to keys, it is, of course, to be understood that it is applicable to other devices as well. 50

What I claim is:—

1. In combination with a key having a flat grip, tactful indicating means arranged in fixed relation thereon thereby to distinguish said key from similarly shaped keys by a sense of touch, said indicating means projecting in a predetermined relation laterally from the flat face of said grip to indicate when the latter is in position for proper 60 insertion in a lock. 55

2. In combination with a key having a flat grip provided with a plurality of holes arranged in predetermined relation in said grip, and indicating means mounted in any 65 one of said holes and projecting in a predetermined relation laterally from the flat face of said grip, whereby the key may be distinguished from other keys of similar shape by a sense of touch. 70

3. In combination with a key having a flat grip provided with a plurality of holes arranged in predetermined relation in said grip, and indicating means mounted in any 75 one of said holes whereby the key may be distinguished from another key of similar shape by a sense of touch, said indicating means projecting laterally from the flat face of the grip and in a predetermined position thereby to facilitate the insertion of the key 80 in the lock in operative position. 70

Signed this 11th day of April, 1924.

HARRY J. NICHOLS.
